CUTOUT FOR ELECTRIC IRONS

Albert Randolph Cheeseman, Toronto, Ontario,
Canada

Application December 23, 1941, Serial No. 424,095

1 Claim. (Cl. 200—137)

My invention relates to improvements in cut-outs for electric irons, and the object of the invention is to devise means for automatically, instantly and permanently cutting out the current when the temperature has reached a pre-determined maximum and so that it cannot be restored until manually operated means is employed for closing the circuit, and it consists essentially of the arrangement and construction of parts all as hereinafter more particularly described.

Fig. 1 is a perspective view of an iron body, the cover being shown by dotted lines to exhibit the construction of my cut-out.

Fig. 2 is a plan of the cut-out mechanism showing the element winding in diagram.

Fig. 3 is an enlarged sectional view through one of the insulated binding posts.

In the drawing like reference characters indicate corresponding parts in the different views.

1 is the body of the iron, 2 the cover shown mostly by dotted lines. 3 indicates the winding of the element provided with terminals 4 and 5. 6 is an expansion rod set freely in a bored orifice 7 formed in the iron body. 8 is a lever pivoted at 9. 10 and 11 are the post terminals of the iron carried by the cover thereof in the usual manner.

10^x is a set screw carried by the end of the lever 8 and provided with a set nut 11^x threaded thereon. 12 is a hook latch pivoted at 13 and connected to the nut 11^x by a wire 11°. 14 is a spring finger secured at 15 to the iron body and engaged by the latch 12 at its free end. By adjusting the set screw the temperature at which the latch disengages is controlled.

16 is a knob located at the outside of the cover 2 and provided with a stem 17 extending through a small orifice 18 formed in the cover and connected to the spring 14 by an insulating connection 19. 20 is an arm extending from the connection 19. 21 and 22 are standards provided with base plates 23 and 24 which are insulated from the iron.

25 is a metallic insulated contact provided with an arm 26 from which extends a vertical contact pin 27. 28 is a rod from which extends a contact arm 29 engaging the pin 27 and a crank arm 30 pivotally connected to the arm 28.

31 represents in diagram the socket connecting the posts 10 and 11. 32 is a wire connecting the terminal 5 and plate 24. 33 is a wire connecting the contact 25 with the insulated binding post

34 having the metallic connection 35 to the post 11 of the iron cover.

The parts 23, 24, 25 and 34 are all insulated from the iron body in a manner similar to that indicated in Fig. 3 and comprising the insulating sleeves 36 and washers 37 and 38 through which the screw 39 extends into the body.

In operation the finger 14 and latch 12 are in engagement.

As the temperature rises, the rod 6 expands forcing the lever 8 outwardly exerting a pull through the set screw 10^x, set nut 11^x and wire 11° on the latch 13 which is thereby drawn out of engagement with the finger 14. The finger then springs up rocking the rod 28 to carry the contact arm 29 out of engagement with the contact pin 27 thus breaking the circuit.

This circuit remains broken until it is manually closed by pressing the knob 16 so as to re-engage the finger with the latch 12 and complete the circuit.

The circuit extends from one terminal 4 of the element winding to the post 10, then by socket 31 to post 11, then by the metallic connection 35 to the post 34 and thence by wire 33 to contact 25 and pin 27 to contact arm 29 and rod 28 returning by wire 32 to the other terminal 5 of the element winding 3.

From this description it will be seen that I have devised a cut-out which will operate rapidly to open the circuit which will then remain open until closed by manual pressure on the knob 16.

What I claim as my invention is:

In an electric iron or other heated device having a heating element and terminals therefor, a thermostatic switch comprising a spring finger, a crank rod of conducting material mounted in suitable bearings one of which forms one terminal of the element, a crank arm extending from the rod and depressed by the depression of the spring finger to rotate the rod, a pin forming the other terminal of the element, a contact arm also extending from the crank rod to engage the pin and adapted to break contact therewith when the crank rod is rotated by the depression of the spring finger, a spring pressed pivoted latch for engaging the end of the spring finger to hold it in the depressed position, and automatic means for operating the latch to free the finger as the temperature of the element rises to maximum and means for reengaging the latch and finger as the element cools.

ALBERT RANDOLPH CHEESEMAN.
